UNITED STATES PATENT OFFICE

2,575,090

INTERCHANGEABLE CLOCK DIAL UNIT
ASSEMBLYMaurice A. Elouin, Gardner, Mass., assignor to
Simplex Time Recorder Co., Gardner, Mass., a
corporation of Massachusetts

Application August 21, 1948, Serial No. 45,457

2 Claims. (Cl. 58—125)

1

This invention relates to clocks or similar devices in which the passage of time is indicated by the movement of hands or other indicators at predetermined speeds over the face of a dial.

The dial is commonly numbered from 1 to 12 but which may be numbered from 1 to 24 to show Continental time. The dial may also vary in shape and style and in system of numbers, and the hands may vary in shape and in relative speed ratio.

It is the general object of my invention to provide a dial unit assembly which may be very easily attached to a clock movement and which may be detached and removed therefrom with equal facility. This invention permits a variety of dial unit assemblies to be carried in stock and to be quickly and easily combined with any required clock movement. A large number of dial-and-movement combinations may thus be built up from a comparatively small number of parts, and shipment of desired combinations is expedited.

Important features of the invention relate to simplified constructions by which the dial unit assemblies may be very easily and quickly attached to the desired clock movements.

The invention further relates to arrangements and combinations of parts which will be herein-after described and more particularly pointed out in the appended claims.

A preferred form of the invention is shown in the drawings, in which

Fig. 1 is a plan view of a portion of an enlarged clock movement, with my improved dial assembly mounted thereon;

Fig. 2 is a front elevation, looking in the direction of the arrow 2 in Fig. 1; and

Fig. 3 is a side elevation, partly in section and looking in the direction of the arrow 3 in Fig. 1.

Referring to the drawings, I have shown parts of a clock movement M including side plates 10 and 11 and a driven shaft 12 having a bevel gear 14 mounted thereon for continuous rotation.

My improved dial unit assembly includes a frame member 20 having a dial 22 secured thereto by screws 23. The dial 22 is shown herein as having its inner portion depressed and provided with a rectangular arrangement of Arabic numerals from 1 to 12, but Roman numerals in a circular arrangement may be used, or the numbers may run from 1 to 24 instead of from 1 to 12.

The middle portion of the frame 20 is upwardly extended as indicated at 24 and is provided with end lugs 25. The frame 20 is also downwardly extended as indicated at 26 and is provided with shoulders 27.

2

Each movement side plate 10 and 11 is provided with upper hooks 30 and lower hooks 31, positioned and spaced to receive the lugs 25 and shoulders 27. The dial unit assembly is thus supported and accurately positioned on the clock movement.

The assembly may be secured in position by a single binding screw 40 engaging a circular groove or recess 41 in a cross pin 42 which extends loosely through openings 44 in the side plates 10 and 11. When the screw 40 is tightened against the pin 42, the pin is firmly seated in the holes 44 and endwise displacement of the rod 42 is prevented. The lugs 25 and shoulders 27 are also held firmly against the side plate hooks 30 and 31, thus firmly securing the dial unit assembly on the clock movement.

The dial frame 20 supports a sleeve 50 which provides a bearing for a minute shaft 51, to the front end of which the minute hand 52 is attached. The shaft 51 has a bevel gear 53 at its rear end which is engaged and driven by the bevel gear 14 on the shaft 12 of the movement M.

The minute shaft 51 has a gear 60 engaging a larger gear 61 loosely mounted on a stud 62 secured in the downwardly extending portion 26 of the frame 20. A pinion 64 is associated with the gear 61 and engages a large gear 65 by which the hour hand 66 is rotated.

If a twenty-four hour dial is used in place of the twelve hour dial shown, the gear train between the shaft 51 and the hour hand 66 will be modified in the usual manner to provide the desired ratio.

This gear train is of the usual type and in itself forms no part of the present invention. It is necessary, however, to set the gear 53 in predetermined angular relation with the minute hand 52, so that the dial assemblies may be interchangeable on the movements M.

Having thus described my invention and the advantages thereof, I do not wish to be limited to the details herein disclosed, otherwise than as set forth in the claims, but what I claim is:

1. In a time clock, a clock movement, a dial unit assembly, means to detachably and interchangeably support and secure said dial assembly on said clock movement, said movement having side plates with forwardly projecting hooks, and said unit assembly having coacting portions engaged by said hooks, and positively-acting means to hold said hooks and coacting portions in assembled relation and comprising a cross pin extending loosely through holes in said side plates and having an annular groove near its center of length, and a screw in said assembly

engaging said pin in said groove and underneath said pin.

2. In a time clock, a clock movement, a dial unit assembly, and means to detachably and interchangeably support and secure said dial assembly on said clock movement, said movement having side plates with upper and lower forwardly-projecting and up-turned hooks on the front edge of each plate and said unit assembly having a frame recessed to provide upper and lower portions extending laterally at each side of the middle portion of said frame and positioned to engage and be supported on said hooks, and positively-acting means effective to hold said laterally-extending portions and coacting hooks 15

in assembled relation and from relative vertical displacement.

MAURICE A. BLOUIN.
